UNITED STATES PATENT OFFICE

102,664

DESIGN FOR A COMBINED CABINET AND X-RAY PICTURE DISPLAY SUPPORT OR THE LIKE

Howell G. Evans, Two Rivers, Wis., assignor to
Hamilton Manufacturing Company, Two Rivers,
Wis., a corporation of Wisconsin

Application June 8, 1936, Serial No. 63,099

Term of patent 7 years

To all whom it may concern:

Be it known that I, Howell G. Evans, a citizen of the United States, residing in Two Rivers, Manitowoc County, Wisconsin, have invented a new, original, and ornamental Design for a Combined Cabinet and X-Ray Picture Display Support or the like, of which the following is a specification, reference being had to the accompanying drawing forming a part hereof.

The figure is a perspective view of a combined cabinet and X-ray picture display support, showing my new design.

The upper part of the cabinet includes a black hood which has a glassed opening therein on a lower margin of which is a lip, on which an X-ray

negative may be supported. An incandescent light within the cabinet illuminates the opening from within and thus shines through the transparent X-ray film to display the latter for the benefit of both physician and patient. The black hood referred to may be raised as a whole to give access to the interior of the cabinet which may contain articles to be used by the dentist in addition to the incandescent light referred to.

I claim:

The ornamental design for a combined cabinet and X-ray picture display support or the like substantially as shown and described.

HOWELL G. EVANS.
